CLAIM

The ornamental design for an showerhead bar with siding spray, as shown and described.

DESCRIPTION

FIG. 1 is a perspective view of my showerhead bar with siding spray design;

FIG. 2 is another perspective view of my showerhead bar with siding spray design as positioned for use;

FIG. 3 is a left side view thereof;

FIG. 4 is a top view thereof shown cut away for ease of illustration; and,

FIG. 5 is a rear view thereof.

The shower head cord in FIGS. 1,2,3 and 5 and the bar in FIGS. 3 and 5 are shown broken away for ease of illustration.
